Primary Examiner — Amy C Wierenga*Assistant Examiner* — Kathryn Elizabeth Zieno(74) *Attorney, Agent, or Firm* — Georgi Korobanov(57) **CLAIM**

The ornamental design for a faucet, as shown and described.

DESCRIPTION

FIG. 1 is a rear, left and bottom perspective view of a faucet, showing my new design;

FIG. 2 is a front, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged detail view of portion 9 shown in FIG. 1.

The evenly spaced broken lines depict portions of the faucet that form no part of the claim. The dot dash broken line indicates cutoff boundaries for the enlarged detail views and forms no part of the claim.

1 Claim, 9 Drawing Sheets(56)
